UNITED STATES PATENT OFFICE.

DOMINIQUE CRESPIN DE LA JEANNIERE, OF PARIS, FRANCE.

AUTOMATIC SAFETY-BRAKE FOR ELEVATORS AND HOISTS.

SPECIFICATION forming part of Letters Patent No. 311,649, dated February 3, 1885.

Application filed September 20, 1884. (No model.) Patented in Belgium August 23, 1884, No. 66,110, and in Italy September 1, 1884, XXXIV, 2/1.

To all whom it may concern:

Be it known that I, DOMINIQUE CRESPIN DE LA JEANNIERE, a citizen of the French Republic, and a resident of Paris, France, have 5 invented certain Improvements in Automatic Safety-Brakes, of which the following is a specification.

My invention relates to an automatic safety-brake especially designed for elevators and 10 hoists, but which is also applicable to automatically arresting any rectilinear movement of a car or body, whether its direction be horizontal, inclined, or vertical. It belongs to that class of automatic brakes wherein the 15 resistance to the movement by the car or other object to be moved serves to hold the brake freed or out of engagement; but if the pulling strain be thrown off or relaxed, as by the breaking of the draft-rope, a spring sets the 20 brake.

My invention consists in the mechanism and arrangement of parts whereby the automatic braking is effected, and this mechanism comprises brake-jaws adapted to clamp on a stationary guide-rod or brake-rod, and special 25 means for operating said jaws when the draft-rope breaks, all as will be particularly described hereinafter.

In the drawings, which serve to illustrate 30 my invention, I have shown it as applied to an elevator or hoist, this being sufficient to illustrate its application to cars on inclined or horizontal tracks as well.

Figures 1 and 2 illustrate my invention in 35 its preferred form, the former being a front and the latter a bottom view or plan. Figs. 3 and 4 illustrate a modification, the former being a front elevation, partly broken away, and the latter a bottom view or plan, also 40 partly broken away.

Referring first to Figs. 1 and 2, A represents an elevator-car arranged in any ordinary elevator-shaft—represented by B, for example—and provided with a hoisting-rope, C. 45 D are ordinary stationary guide-rods, which serve to guide the car in its reciprocating movement, and also serve as brake-rods, or rods on which the brake-jaws clamp. The hoisting-rope C is not attached directly to the car A, 50 but to a frame, E, comprising a cross bar or tie, a, which connects two side rods, b b, which

play in keepers c on the sides of the car, and are provided at their lower ends with brackets d d, on which rests a cross beam or sill, e. These parts form the hoisting frame E. The 55 car A rests on a spring or springs, f, which are interposed between its bottom and the beam or sill e.

On the car A are bearing-brackets g g, two at each side, in which are mounted rotatively 60 shafts h h, each of which has right and left screw-threads formed on it, which engage female screws in two brake-jaws, i i. These jaws are in the nature of bars that extend across under the car above beam e, and their 65 clamping ends embrace the two guide-rods D D, as clearly shown. On the screw-shafts h are fixed pinions j j, one on each shaft, and on the side rods, b, of frame E are formed or secured racks k k, which mesh with said pinions. 70

The operation is as follows: When the car is suspended properly, its weight serves to compress the springs f. This compression causes the car to descend a little in frame E, and, carrying pinions j with it, to cause their 75 partial rotation by reason of their engagement with racks k. The partial rotation of the screw-shafts h produced by this separates the jaws i of the brake far enough for them to stand clear of the guide-rods, or at least not to 80 clamp on said rods, while at the same time they serve to guide the car on said rods.

The above-described condition is the normal one when the car is suspended from the hoisting-rope; but in case the said rope should break, 85 then the springs f would be relieved of tension and would force down the suspending frame E, and with it the racks k. These would act to rotate the pinions j and screw-shafts h, and these would cause the clamp-jaws i to forcibly 90 clamp the guide-rods and arrest the descent of the car. The movement of the brake-jaws need not be great, as it is only designed that they shall separate far enough to permit the guide-rod to move freely between them. The 95 faces of the jaws may be roughened, if desired. The modification in Figs. 3 and 4 shows substantially the same construction, differing only in this, that a lever-nut takes the place of the rack and pinion device. The 100 screw-shafts h are fixed in brackets g, secured to the bottom of the car. The brake-jaws i are

in the form of lever-nuts, the fulcrums being on screw-shafts *h*. The jaws embrace the guide-rods at one end, and are coupled together by a link, *l*, at the other end, which link is connected to the rods *b* of the hoisting-frame *E*. Springs *f*, which encircle rods *b*, are arranged between the coupling-links *l* and the bottom of car.

- 5 F is a tie-bar connecting brackets *g*.
 10 In this modification the hoisting-rope is supposed to be broken and the jaws clamped on the guide-rods.

15 In the form illustrated in Figs. 1 and 2 the brake-jaws move up to the guide-rod in parallel planes or like the jaws of a parallel vise.

20 In Figs. 3 and 4 the fulcrum-axis of the jaws is the same as in Figs. 1 and 2; but the jaws are not parallel in fact, but nearly so. In both, the brake-jaws serve to guide the car in its movement normally, and in case of the accidental breaking of the hoisting-rope the brake-jaws act frictionally and do not stop the car suddenly, as does the well-known safety-ratchet device. The power of the brake is of course dependent on the tension of spring *f*; but a comparatively light spring will serve, as its power is multiplied by the screw and rack and pinion.

25 I am aware that friction safety-brakes have before been proposed for elevators, and that such have been constructed to be set by a spring when the hoisting-rope breaks. Therefore I do not claim this, broadly.

30 I am also aware that screws have been used or proposed to be used for setting friction safety-brakes on elevators, said screws being adapted to be rotated so as to set the brakes by means of the resistance offered by the rapid

upward movement of a packed weight in a shaft when the car descends with unusual velocity. 40

This device may operate to set the brakes when the hoisting-rope is under full tension and unbroken.

In my brake the speed with which the car descends does not control the operation of the 45 brake, and the latter is set instantly when the hoisting-rope is severed.

In the device just referred to the rapid descent of the car is necessary to the operation of the brake.

50 Having thus described my invention, I claim—

1. The combination, with a car, *A*, its hoisting-frame *E*, hoisting-rope *C*, and springs *f*, of the screw-shafts *h*, provided with right and left screw-threads, the brake-jaws *i*, mounted on said shafts, as described, and the means described for causing the jaws to clamp on the guide-rods when the weight of the car is taken off the spring *f*, as set forth. 55

2. The combination, with a car, *A*, its hoisting-frame *E*, hoisting-rope *C*, and springs *f*, of the screw-shafts *h*, mounted in rotative bearings on the car and provided with right and left screws, the pinions fixed on said screw-shafts, the racks on the hoisting-frame, and the brake jaws provided with female screws and mounted on the screw-shafts, substantially as shown and described. 65

60 In witness whereof I have hereunto signed my name in the presence of two subscribing witnesses.

DOMINIQUE CRESPIN DE LA JEANNIERE.
